CLAIM

The ornamental design for a pistol-gripped magnetic wand for bingo chips, as shown and described.

DESCRIPTION

FIG. 1 is a perspective view of the pistol-gripped magnetic wand for bingo chips showing my new design; FIG. 2 is a side elevational view thereof;

FIG. 3 is a side cross-sectional view thereof, taken along the line 3—3 in FIG. 4;

FIG. 4 is a front elevational view thereof;

FIG. 5 is a rear elevational view thereof;

FIG. 6 is a top plan view thereof; and,

FIG. 7 is a bottom plan view thereof.
